UNITED STATES PATENT OFFICE

PAUL J. STUPARICH, OF SAN FRANCISCO, CALIFORNIA

DESIGN FOR A PHOTOGRAPHIC MOUNT

Application filed February 6, 1933. Serial No. 47,129. Term of patent 3½ years.

To all whom it may concern:

Be it known that I, PAUL J. STUPARICH, a citizen of the United States, residing at San Francisco, in the county of San Francisco and the State of California, have invented a new, original, and ornamental Design for a Photographic Mount, of which the following is a specification, reference being had to the accompanying drawing, forming part thereof.

Figure 1 is a plan view of a photographic mount showing my new design, and the diag-

onal lines shown indicate surface shading and not color.

Figure 2 is an edge view of the same, partly in perspective, showing the two top sheets turned slightly away from the back section to permit the insertion of the photograph to be mounted therein.

I claim:

The ornamental design for a photographic mount, as shown and described.

PAUL J. STUPARICH.
